WALL SWITCH

Robert I. Innis, Winthrop, Mass.

Application February 17, 1938, Serial No. 190,992

5 Claims. (CL. 206—168)

My invention relates to wall switches such as are installed in homes, offices and other places for controlling electric lighting circuits and the like, and to ornamental cover attachments for existing switches of that class.

The invention has for its object to improve the construction and appearance of electric switches of the class described.

It is a further object of this invention to provide an improved wall switch of the character shown and described in my co-pending application filed January 3, 1938, Serial Number 183,081.

To these ends I have provided an improved wall switch of the character described having the features of construction and mode of operation set forth in the following description, the several novel features of the invention being particularly pointed out and defined in the claims at the close thereof.

20 In the accompanying drawing:—

Figure 1 is a front elevation, partly broken away and in section, of a wall switch mechanism constructed in accordance with this invention.

Figure 2 is a section on line 2—2 of Fig. 1.

Figure 3 is a detail hereinafter described relating to the switch illustrated in Figs. 1 and 2.

Figure 4 is a front elevation, partly broken away and in section, of a wall switch mechanism embodying an alternative construction.

30 Figure 5 is a section on line 5—5 of Fig. 4.

A common form of wall switch comprises a porcelain body 10 equipped with a metal bridge bar 12 which is fastened at its opposite ends to a metal switch box 13 by screws 18, said box being incorporated within the wall 14 of the room. The body 10 contains the make and break mechanism of the switch, as usual, and in Figs. 1 and 2 this mechanism is operated by means of two push-buttons 15 and 15' while in Figs. 4 and 5 it is operated by a lever 16. Ordinarily the bridge bar 12 is provided with threaded apertures to receive two screws 11 by means of which a face plate 17 is secured to the bridge bar 12, the marginal portion of said face plate overlying the part of the wall adjacent to the box 13. The face plate 17 is, as usual, molded from sheet metal into a dish-like shape and so as to provide the same with a beveled outer edge as shown at 17'.

In the case of push-button switches the face plate 17 is made near its middle with two holes or apertures as shown in Fig. 2 through which the push-buttons 15 and 15' project to the exterior of the face plate where they were heretofore accessible for direct manual operation, while in the case of lever switches of the type shown in Figs. 4 and 5 the face plate 17 was made with a single aperture 11a through which the lever 16 projected to the exterior of the plate 17 where it was heretofore accessible for direct manual operation.

The embodiment of my invention illustrated in Figs. 1, 2 and 3 comprises a rocker member 19 disposed between the two push-buttons 15 and 15', said rocker member being pivotally connected at 20 to one end of a resilient metal leaf 5 spring 21 which is fastened intermediate its ends to the outer side of face plate 17 by one of the screws 11. At its opposite or outer end the leaf spring 21 is pivotally connected at 22 to a hand lever 23, said pivot 22 serving as the fulcrum for 10 said lever.

The lever 23 is connected by a link 24 with the rocker member 19 so that when lever 23 is swung on its fulcrum 22 it acts through the link 24 to swing rocker 19 on its pivot 20. The rocker 19 15 is constructed with two oppositely disposed arms 25 each disposed opposite the outer end of one of the push-buttons. It will therefore be clear that when the hand lever 23 is swung upwardly into the position indicated by dotted lines in 20 Fig. 2 it will act through the link 24 to swing rocker 19 upwardly and cause the same to force the push-button 15 inwardly and this inward movement of push-button 15 is accompanied, as usual, by corresponding outward movement of 25 push-button 15'. It will also be clear that when hand lever 23 is swung downwardly into the position shown in full lines in Fig. 2 it will act through the link 24 to angularly adjust rocker 19 on its pivot 20 in a direction to force push-button 15' inwardly and push-button 15 outwardly.

With different switches of the push-button type I find that the buttons thereof do not always project through or beyond the face plate, always 35 exactly the same distance. That is to say, the distance the buttons project beyond the face plate of different switches often varies as much as $\frac{1}{8}$ of an inch, and in order to provide for this variation I have found it desirable, if not essential, 40 to provide a resilient support for the rocker member 19 such as the leaf spring 21 which is of sufficient stiffness to insure operation of the push-buttons by the rocker member and yet sufficiently resilient to permit the rocker member 19 to fit 45 itself to the push-buttons whatever be the relation of the latter to the face plate 17.

The link 24 is a bail-shaped wire member having an intermediate portion pivotally mounted within an eye 26 provided on the lever 23 and 50 having the extremities of its branches or legs pivotally connected at 27 to the rocker member 19.

The rocker supporting leaf spring 21 is secured in position against the outside of the usual face plate 17 by means of the original screws 11 after 55 said face plate has been removed and replaced in reversed position as shown. The purpose in reversing the face plate 17 is to adapt it to receive upon it and support a molded cover member 28 which is formed upon its inner side or face 60

with a recess 29 that is open at its lower end but bordered at its top and opposite sides by marginal walls or flanges 30 and 31, respectively, the inner sides of said walls or flanges being beveled or 5 undercut to fit the outwardly flaring beveled edge 17' of the face plate 17. Thus the side walls or flanges 31 provide the cover member 28 with a vertical or longitudinal dovetail groove which permits the cover member 28 to be applied to and 10 interlocked with the face plate by sliding said cover member downwardly from above until the top wall or flange 30 abuts the upper end of the face plate 17 as shown.

A feature of advantage residing in the above 15 described construction is that the operating lever 23 has its free end portion disposed outside of the cover member 28 and away from the wall 14 within which the switch is installed so that the fingers of the hand operating lever 23 are prevented 20 from contact with the wall so that soiling of the latter is prevented.

The cover member 28 is preferably a molded product designed for ornamental effects, particularly upon its exterior, and so as to cover and 25 hide from view all of the original switch mechanism and all of the switch operating attachment except the lever 23. This lever 23 is also preferably a molded product. Suitable materials for use in producing the parts 23 and 28 are "Bakelite", hard rubber and the like but, of course, said parts may be produced otherwise if desired.

In the embodiment of my invention illustrated in Figs. 4 and 5 I provide a cross-head or slide 32 which is slidably mounted between the outer side 35 of the face plate 17 and a resilient metal leaf spring 21a. The cross-head or slide 32 is formed at its middle with an aperture through which the lever 16 of the switch extends and at one end is made with an ear or lug 33 extending outwardly 40 through a slot 34 at the inner end of the leaf spring 21a. The lug or ear 33 is pivotally connected at 35 to one end of a bail-shaped link 36 whose opposite end is pivotally connected to a lever 23 that is pivotally connected at 22 to the 45 outer or lower end of the leaf spring 21a. The leaf spring 21a yieldingly urges the cross-head or slide 32 toward the face plate 17 and the hub of lever 16 but it will be clear that when lever 23 is swung on its pivot 22 it will act through the 50 link 36 and the cross-head or slide 32 to operate the lever 16 thereby to open and close the switch. The resiliency of the spring 21a permits the cross-head or slide 32 to fit itself to the lever 16 whatever 55 be the relationship between said lever and face plate 17.

When installing the wall switches of this type the box 13 does not always bear the same relationship to the outer surface of the wall so that the distance between the face plate which is outside 60 of the wall and the box 13 by which the switch 10 is supported will often vary, sometimes as much as $\frac{1}{8}$ of an inch, with the result that the lever 16 may project through the face plate more or less but the resiliency of the spring 21a permits the cross-head or slide 32 to accommodate itself to the lever 16 whatever be the relationship 65 between said lever and the face plate.

What I claim is:

1. The combination with an existing wall switch 70 of the character described comprising a body adapted to be fixed within a cavity of the wall, an apertured face plate fixed to said body whose marginal portion overlies the outer face of the wall adjacent to said cavity, and switch-operating mechanism projecting from said body

through said apertured face plate to the exterior thereof, of an actuator element engaging said switch-operating mechanism, said element being disposed outside of said face plate, a resilient support for said actuator element by which the latter is yieldingly urged toward said switch-operating mechanism, means fastening said support to said face plate, a finger lever pivotally mounted upon said support adjacent to the lower end of said face plate, means connecting said finger lever with said actuator through which said finger lever adjusts said actuator when it is swung on its pivot, a hollow cover inclosing and concealing said face plate, said switch-operating mechanism and said actuating mechanism with the exception of said finger lever, and means by which said cover is attached to said face plate.

2. The combination of claim 1 wherein said resilient support is a metal leaf spring.

3. The combination of claim 1 wherein said resilient support is a metal leaf spring and wherein 20 said leaf spring is secured in position against the outer side of said face plate by a screw that is part of the existing wall switch.

4. The combination with an existing wall 25 switch of the character described comprising a body adapted to be fixed within a cavity of the wall, an apertured face plate fixed to said body whose marginal portion overlies the outer face of the wall adjacent to said cavity and switch-operating mechanism including push-buttons projecting from said body through said apertured face plate to the exterior thereof, of a rocker element 30 for actuating said push-buttons, said rocker element being disposed outside of said face plate, a resilient support on which said rocker element is pivotally mounted and by which the latter is yieldingly urged toward said push-buttons, means fastening said resilient support to said face plate, a finger lever pivotally mounted upon said support adjacent to the lower end of said face plate, means connecting said finger lever with said 35 rocker element through which said finger lever adjusts said rocker element when said finger lever is swung on its pivot thereby to operate said push-buttons, a hollow cover inclosing and concealing 40 said face plate, said push-buttons and said push-button actuating mechanism with the exception of said finger lever, and means by which said cover is attached to said face plate.

5. The combination with an existing wall 50 switch of the character described comprising a body adapted to be fixed within a cavity of the wall, an apertured face plate fixed to said body whose marginal portion overlies the outer face

55 of the wall adjacent to said cavity, and switch-operating mechanism including a switch lever projecting from said body through said apertured face plate to the exterior thereof, of a cross-head 60 slidably fitted against the outer side of said face plate and engaging said switch lever, a leaf spring 65 yieldingly holding said cross-head in position against said face plate, means fastening said leaf spring in position against the outer side of said face plate, a finger lever pivotally mounted upon said leaf spring adjacent to the lower end of said face plate, means connecting said finger lever with said cross-head through which said finger lever adjusts the latter when it is swung on its pivot, a hollow cover inclosing and concealing 70 said face plate, said switch lever and said lever actuating mechanism with the exception of said finger lever and means by which said cover is attached to said face plate.
